UNITED STATES PATENT OFFICE.

HARRY W. CRANE, OF PHILADELPHIA, PENNSYLVANIA, ASSIGNOR TO INTERNATIONAL WINDOW MANUFACTURING COMPANY, A CORPORATION OF DELAWARE.

SASH-PIVOT CONSTRUCTION.

1,171,773.

Specification of Letters Patent.

Patented Feb. 15, 1916.

Application filed November 19, 1913. Serial No. 801,774.

To all whom it may concern:

Be it known that I, HARRY W. CRANE, a citizen of the United States, residing at Philadelphia, county of Philadelphia, and 5 State of Pennsylvania, have invented a new and useful Improvement in Sash-Pivot Construction, of which the following is a full, clear, and exact description, reference being had to the accompanying drawings, 10 which form a part of this specification.

My invention relates to windows, and particularly to that class in which counterbalanced sashes, in addition to having a vertical movement in a window frame, are 15 capable of swinging on a horizontal axis midway between the upper and lower ends. Such a window is set forth in the patent to George, No. 776,177, dated November 29th, 1904.

20 The object of my invention is to improve the construction of the window of that patent and more particularly to provide improved means for pivotally mounting the sash upon the supplemental stile or shoe and for holding the sash in any position to which it may be swung. This object is attained by a novel construction and arrangement the essential features of which are pointed out in the claims and a preferred 25 specific embodiment of which is described in the following specification and particularly illustrated in the accompanying drawings, in which—

Figure 1 is a perspective of the window frame, the sash and the shoe or supplemental stile, all partly broken away, with the sash partly swung open. Fig. 2 is a perspective of the sash with the shoe and certain parts of the pivotal connection removed. Fig. 3 is an inside face view of the shoe. Fig. 4 is an inside face view of the sash. Fig. 5 is a longitudinal section through the central part of the shoe and sash. Fig. 6 is a section on the line 6—6 of 40 Fig. 5. Fig. 7 is a section on the line 7—7 of Fig. 5.

a indicates the window frame the same being provided with the three vertical parting-beads b, b, b, forming two grooves or run-ways c, c, in which slide the stiles 50 of the two sashes. In the drawings I have, for convenience, shown only lower sash *a* as pivoted on a sliding shoe, the upper sash *d* being unprovided with a special shoe and being similar to the upper sash of an ordinary double-hung window; but it will be understood that my invention may be applied to either or both sashes. In the inner of the two grooves *c* is a slidable shoe *e*, which is of substantially the length of the 55 sash which it sustains and is of a thickness somewhat greater than the depth of the groove in which it slides. About midway between the ends of the shoe the same is cut away between its front and rear faces to 60 form a recess *f*. The edges of the shoe adjacent to the face thereof opposing the sash are rabbeted, as at *g*. The edges of the sash *a* adjacent to the face thereof opposing the shoe are similarly rabbeted as at *h*. 70

A plate *i* extending from the upper to the lower end of the shoe, is applied and secured to the face of the shoe opposing the sash. The plate is offset at its central portion to fit into the recess *f*. At opposite ends the 75 plate *i* is T-shaped. At one end, say the upper end, of the plate *i*, the head of the T is at the outside of the shoe, one angle thereof extending into the outside rabbet of the shoe and the other angle extending, 80 when the sash is closed, into the outside rabbet of the sash. At the other end, say the lower end, of the plate *i*, the head of the T is at the inside of the shoe, one angle thereof extending into the inside rabbet of 85 the shoe and the other angle extending, when the sash is closed, into the inside rabbet of the sash. Each T-head of the plate *i* extends from one end of the shoe toward the pivot of the sash but does not extend as 90 far as the pivot.

A plate *j*, extending from the upper to

the lower end of the sash, is applied and secured to the face of the sash opposing the shoe. This plate is also T-shaped at opposite ends. At one end, say the upper end, of 5 the plate *j*, the head of the T is at the inside of the sash, one angle thereof extending into the inside rabbet of the sash and the other angle extending, when the sash is closed, into the inside rabbet of the shoe. 10 At the other end, say the lower end, of the plate *j*, the head of the T is at the outside of the sash, one angle thereof extending into the outside rabbet of the sash and the other end extending, when the sash is closed, into 15 the outside rabbet of the shoe. Each T-head of the plate *j* extends from one end of the sash toward the pivot thereof and beyond said pivot to such a distance that, when the sash is closed its end abuts against the 20 corresponding T-head of the shoe. It will be understood, however, that the relative lengths of the T-heads of shoe and sash may be the reverse of that described. The heads of the T are preferably formed by bending 25 the metal of the plate first in one direction, then in the other direction and then back again to the leg of the T, thus forming from a single piece of metal a T-shaped plate whose head is of twice the thickness 30 of its leg.

At the center of the depression *f* the shoe is formed with a circular orifice *h* extending from the base of the depression, or the face of the shoe opposite the sash, to the face 35 of the shoe sliding in the groove in the frame. Immediately opposite this orifice the sash is provided with a recess *l* of similar cross-section. This recess and orifice are adapted to receive the pivot pin or bolt 40 *m*, the head *n* of which extends into the recess *l*. A collar *o* provides a bearing for the bolt. This collar is provided with a flange which overlaps the recess *l*, the overlapping edge of the flange being countersunk and secured in the face of the sash. 45 The neck of the collar *o* extends within an orifice formed by annular flanges bent toward each other from the plates *i* and *j*. A filler ring *z* extends between the plates *i* and *j* and surrounds the inturned flanges 50 thereof.

A cup-shaped spring washer *p*, sleeved on the bolt *m*, is confined between the plate *i* and two nuts *r*, *r*, threaded on the bolt. The 55 bolt *m* has a neck engaging a slot in a locking plate *s*, which is countersunk in the working face of the shoe *e*. This holds the bolt from turning.

The offset part of the plate *i*, or that part 60 thereof which fits into the base of the recess *f*, is provided, above and below the pivot, with vertically extending shallow depressions or pockets *u* which fit into corresponding depressions in the base of the recess *f*. 65 In the space, with the recess *f*, between the

plates *i* and *j*, and above and below the pivot, is a flanged holding plate *t* having ridges *v* adapted to the depressions *u*. Springs *w*, confined between the plate *i* and the holding plate *t*, hold the plate *t* tightly 70 against the plate *i* and the ridges *v* within the depressions *u*, when the sash is closed.

By the above construction the sash *x* is prevented from turning from its closed position unless a degree of force is exerted sufficient to force the holding plate *t* out of its pocketed engagement with the plate *i*, against the action of the springs *w*. In turning the sash the holding plate overrides the non-pocketed faces of the offset part of 80 the plate *i* and frictionally resists turning, whereby the sash is held open at any angle to which it may be moved. When the sash is turned to its closing position, or in parallelism with the shoe *e*, the ridges *v* are 85 brought opposite the depressions *u*, and engage therewith by the action of the springs *w*, thus holding the sash closed. The opposing frictionally engaging parts of the shoe and sash are wholly of metal, rendering the 90 construction very durable. When the sash is closed the closure is weather-tight, the only possible opening for admission of air being closed by a block *y*, secured to or integral with the head of the T-shaped upper 95 end of the plate *i*, said block extending across the central parting bead *b* and closing the space between the shoe *e* and the upper sash *d*.

Having now fully described my invention, 100 what I claim and desire to protect by Letters Patent is:

1. A sash pivot construction comprising two members shaped to form between them an elongated recess and flanged to form an 105 opening for a pivot, a collar within said opening, a filler ring surrounding said flanges, tension devices within said recess on opposite sides of the pivot opening tending to maintain said members in the angular relation into which they are moved, and a pivot pin extending through the collar.

2. A sash pivot construction comprising two members shaped to form between them an elongated recess and flanged to form an opening for a pivot, a collar within said recess having a flange underlying one of said members, a pivot bolt extending through said collar, a head on the bolt contacting with the flange of the collar, a nut on said bolt, a spring washer confined by said nut against one of the said members, and tension devices within said recess on opposite sides of the first opening tending to 115 maintain said members in the angular relation into which they are moved.

3. A sash pivot construction comprising two members shaped to form between them an elongated recess, a pivot pin extending through said recess, a bearing surrounding 120

the pin and a filler ring surrounding the bearing, holding plates within said recess on opposite sides of the filler ring, each plate having flanges adapted to said recess, and a spring within said recess holding said plate in frictional contact with one of said members.

In testimony of which invention, I have hereunto set my hand, at Philadelphia, on this 28th day of October, 1913.

HARRY W. CRANE.
